JOHN B. LORANGER, OF DETROIT, MICHIGAN.

TABLE FOR PAPER-HANGERS.

1,147,255.

Specification of Letters Patent. Patented July 20, 1915.

Application filed August 7, 1912. Serial No. 713,721.

To all whom it may concern:

Be it known that I, JOHN B. LORANGER, a citizen of the United States, residing at Detroit, county of Wayne, State of Michigan, have invented a certain new and useful Improvement in Tables for Paper-Hangers, and declare the following to be a full, clear, and exact description of the same, such as will enable others skilled in the art to which it pertains to make and use the same, reference being had to the accompanying drawings, which form a part of this specification.

This invention relates to tables for paper hangers and has for its object a table that is convertible into the form of a case so that it may be carried on street cars.

In the drawings, Figure 1, is a longitudinal section of the table. Fig. 2, is a perspective of the table. Fig. 3, is a detail of one of the brackets upon which the straight edge may be rested. Fig. 4, is a cross section of the table converted into a case. Fig. 5, is a perspective of the table converted into a case.

The top of the table is made in the form of two half-boxes A and B. These box portions are hinged together at their ends by the hinges 1. At the opposite ends of the box portions, a pair of legs 2 are pivoted on the inside of the box portions. These legs are connected by cross braces 3. The braces 4 are hinged to the meeting ends of the box portion on the inside by the hinges 5. On the ends of the braces are hooks 6 which can be engaged with the plates 7 that are carried by the cross braces 3 and bent out at their centers for the reception of the hooks 6. At one side of the table or the box portions are a pair of slots 8 through which slide the arms 9 (shown in Fig. 4,) when the table is set up. These may be drawn out and another board properly placed on them to widen the table.

One end of one box portion is provided with the hooks 10 and the opposite end of

the other box portion is provided with screw-eyes 11, so that when the table is folded up 45 in the position shown in Fig. 5, the two box portions may be hooked together, forming a case, in appearance like a suit case, and it may be carried by the handles 12. This case acts as a container in which brushes, straight 50 edges and other tools may be carried.

A pair of brackets 13 serve to guide the arms 9 which reciprocate in and out of the box portions.

14 are brackets that are pivoted to the in- 55 side of two of the legs, one for each pair on one side, so that the brackets may be swung out, as shown in Fig. 2, to hold the straight edge when it is not in use. These brackets each have a turned-over end 15, which en- 60 gages a side of the leg so as to prevent the arms from swinging down when carrying the straight edge.

What I claim is:—

In a paper-hanger's folding table, which 65 comprises a pair of half-box portions hinged together so that they can be folded together and locked in place, to be easily carried around, and a pair of supporting legs that fold into the box-like portions, the said box- 70 like portions being provided on one side with a slot in each one, the combination of a pair of brackets secured to the underside of said box-like portions, one in alinement with each slot, and a pair of arms, one guided in each 75 slot and bracket, and each of such length so that it can be completely withdrawn into the casing formed by the two folded box-like portions when secured together, substantially 80 as described.

In testimony whereof, I sign this specification in the presence of two witnesses.

JOHN B. LORANGER.

Witnesses:

STUART C. BARNES,
VIRGINIA C. SPRATT.
